COMBINATION LOCK

Claude J. Amo, Ogdensburg, N. Y.

Application July 7, 1948, Serial No. 37,481

17 Claims. (Cl. 70—138)

1

This invention relates to a lock, and more particularly to a permutation lock assembly for use on panel type doors for small receptacles.

For application to small sheet metal receptacles, such as a house type mail box, it is desirable to have a lock mechanism which will provide an adequate degree of security without being too complicated or expensive. In accordance with the teaching of my invention, I achieve this aim by providing a lock in which the elements of the lock itself are made of relatively inexpensive metal parts arranged in a permutation assembly for adequate security, the number of lock parts needed being small for the security obtained. Thus the complexity and cost of the lock are more properly proportioned to the complexity and cost of the receptacle itself thereby avoiding the use of a relatively heavy lock mechanism which will provide more security and cost more than the nature of the receptacle itself warrants.

It is, accordingly, an object of my invention to provide a new and improved simplified permutation lock assembly for use on doors for small receptacles.

It is another object of my invention to provide such a lock assembly in which the permutation mechanism is housed primarily behind a panel type door and in a housing which forms an operative part of the lock mechanism, said permutation mechanism being actuated from the front of the door.

It is a further object of my invention to provide such a lock assembly in which the permutation mechanism extends through a panel type door but is positioned primarily behind the door and is hidden from view from the rear of the door by a housing which forms an operative part of the lock mechanism, said housing being operably connected to a member actuatable from in front of the panel type door.

It is still another object of my invention to provide such a lock assembly in which the permutation mechanism is housed, in main part, in a housing behind a panel type door, said housing normally engaging a catch member against movement and said housing being movable from the front of the panel type door when the permutation mechanism is correctly set.

It is a still further object of my invention to provide a new and improved permutation lock which includes tumbler members housed in a housing movable by actuation of an operating member extending through said tumblers.

It is still another object of my invention to provide a new and improved door catch member in a lock assembly for a door.

2

These and other objects and advantages of my invention will become apparent from the following detailed description, taken in conjunction with the attached drawings in which:

5 Fig. 1 is a rear perspective view showing the lock housing and a panel type door assembly;

Fig. 2 is a vertical sectional view taken axially of the lock assembly with the depressible operating spindle being shown in natural side elevation;

10 Fig. 3 is a front view of the lock assembly showing the index ring arrangement;

Fig. 4 is a sectional view taken on line 4—4 of Fig. 2; and

15 Fig. 5 is a sectional view taken on line 5—5 of Fig. 2.

Referring to the drawings, and more particularly to Fig. 2, the main elements of the panel lock assembly are the panel type door 10, the permutation mechanism indicated generally by the reference numeral 11, the housing 12 which contains the major portion of the permutation mechanism 11, and the door catch member 13, which is engaged by portions of the housing 12. The door catch member 13 is positioned between the door 10 and a backing plate 14, which, in main part, is spaced from the door 10, being connected thereto at flange portions 15 and 16 by means such as metal screws 17. Of course, spot welding could be employed in place of the metal screws 17.

20 The permutation mechanism 11 extends through an opening in the door 10 and, as mentioned above, the bulk of this mechanism is positioned within the housing 12 on the rear side of door 10. The housing 12 has portions 18 and 19 which extend into openings 20 and 21, respectively, in the door catch member 13 whereby these housing portions engage the catch member 13 to maintain the catch member in door lock position. From this generalized description

25 it can be seen that the housing 12, besides enclosing the major portion of the permutation mechanism 11, also forms an operative part of the lock mechanism since the housing engages the door catch member 13 and the lock can be released only when the housing is moved out of engagement with the catch member. The assembly of the various parts just described is such

30 that the bulk of the lock lies on the rear side of the panel type door 10 and the only part of the lock which projects from the front of this panel type door 10 is that part of the permutation mechanism 11 which, as will be described

35 more fully hereinafter, is used to set, or position, the permutation mechanism and is operated to release the housing 12 from engagement with the

catch member 13 and, further, is used to rotate the catch member itself.

For a more detailed description of the permutation mechanism 11 reference is again made to Figure 2 of the drawings. As shown there, this permutation mechanism includes an outer rotatable tumbler 22, an inner rotatable tumbler 23, and an operating spindle member 24. The parts 22-24 are arranged such that the spindle 24 is located axially of the tumblers 22 and 23 and the latter are, of course, concentric with the spindle and with each other. The outer tumbler 22 is guided within a collar portion 25, which is formed integrally with the backing plate portion 14. While this collar 25 is shown as being integral with part 14, it is, of course, obvious that it could be separate and merely attached to the part 14.

The spindle member 24 includes a reduced diameter portion 26 which extends through an opening 27 located at the rear of the inner tumbler 23. A shoulder 28 is provided on this inner tumbler 23, adjacent the opening 27 therein, and this shoulder 28 is oppositely disposed with respect to a shoulder 29 located on the spindle member 24 where the reduced diameter portion 26 commences. Between the shoulders 28 and 29 a coil spring 30 is located which biases the spindle member 24 outwardly toward the front of the panel type door 10.

Each of the tumbler members 22 and 23 is provided with a lock fence and also with an index ring. For example, the outer tumbler 22 has a fence ring 31 attached thereto adjacent the rear end of the tumbler. This fence ring 31 is a snap-on type metal ring which grips the outer surface of the tumbler sufficiently strongly so that the fence ring will maintain a given position but can be adjusted if desired whereby the lock setting can be varied if it is desired to change the combination numerals which must be set to enable release of the lock. In order to facilitate this assembly, the fence ring 31 is seated in a shallow groove 32 formed adjacent the rear end of tumbler 22. This fence ring 31 contains a gap 33 for a purpose hereinafter described. In similar manner, a snap-on type fence ring 34 is attached adjacent the rear end of the inner tumbler 23 and this fence ring contains a gap 35.

As was mentioned above, the outer tumbler 22 is guided within and by the collar portion 25 of backing plate member 14. This tumbler member extends through an opening 36 in the panel type door 10 and is retained in place with respect to this opening by means of a snap-on type clamp ring 37. The forward end of the tumbler 22 is stepped down to provide a shoulder portion, as shown in Figure 2, for receiving an index ring 38. Flattened portions 39 and 40 are provided on the stepped down portion of the front end of the tumbler 22 and the index ring 38 has correspondingly shaped portions which engage the flattened portions 39 and 40 to maintain the index ring against rotation with respect to the tumbler 22. As will be evident to those skilled in the art, what has just been described is a common means of keying an index ring to a tumbler end and I find this arrangement to be quite sufficient for my purposes. While no set screw is shown for maintaining the index ring in fixed position with respect to the tumbler 22, such could be provided if desired. For most applications, a simple press fit of the parts will be sufficient.

The inner tumbler 23 is supported with respect

to the outer tumbler 22 in essentially the same manner as the latter is supported with respect to the panel type door 10 and the collar portion 25. In other words, the inner tumbler 23 is guided within the outer tumbler 22 and is provided with a snap-on ring clamp 41 adjacent the front end of the inner tumbler. This ring 41 bears against the front edge of the outer tumbler 22 and prevents slippage inward of the inner tumbler with respect to the outer tumbler. The inner tumbler 23 is also provided with a stepped down front end portion containing flats 42 and 43 which engage correspondingly formed portions on index ring 44 to maintain the index ring against rotation with respect to the tumbler. Accordingly, it is seen that each tumbler contains an index ring and that these index rings are arranged so that the front of each ring is visible.

The cup-shaped housing 12 is rigidly attached to the end of the stepped down portion 26 of spindle 24 by means such as the metal screw 45. Housing 12 is concentric with respect to the tumblers 22 and 23 and hence the spindle 24 is located axially of the housing. The housing has a pair of projections 46 and 47 extending inwardly thereof. These projections are aligned in a direction parallel to the longitudinal axis of the housing, i. e. parallel to the spindle member 24 and are located, respectively, adjacent fences 34 and 31. The projections 46 and 47 are of such size that they can pass through gaps 35 and 33, respectively, when these gaps are aligned but will abut against the fences if one attempts to move the housing back when the gaps are not aligned with respect to the projections. A guide pin 48, attached to the collar portion 25 of backing plate 14, engages the walls of a slot 49, formed in housing 12, to keep the housing in alignment such that projections 46 and 47 remain in uppermost position.

As has been mentioned above, the housing 12 contains portions 18 and 19 which extend into openings 20 and 21 provided in the door catch member 13. These portions 18 and 19 are in the form of extension lugs and they, of course, also extend through openings 50 and 51 in the backing plate 14 which openings correspond in size and shape to the openings 20 and 21. The door catch member 13, which is engaged against movement by the portions 18 and 19 of the housing when the lock is in locked position, is shown in greater detail in Figures 4 and 5. Referring to these figures, it is seen that this catch member includes two arcuate semicircular portions 52 and 53 which substantially completely encircle the outer tumbler 22. Oppositely disposed ear portions 54 and 55 are formed on corresponding opposite ends of portions 52 and 53 and these ear portions are maintained adjacent each other by a nut and bolt assembly 56 which includes a tensioning spring 57 for bias of the parts toward each other. At the opposite side of arcuate portions 52 and 53 an ear portion 58 is formed on arcuate portion 53 and a latch member 59 is formed as an extension of arcuate portion 52. Parts 58 and 59 are maintained in juxtaposition by means of a nut and bolt assembly 60 including a take-up spring 61 to provide bias of the parts toward one another. The inner surfaces of arcuate portions 52 and 53 are lined with a friction liner 62, preferably leather, which closely engages the outer surface of tumbler 22 in response to the urging of springs 57 and 61.

In the assembly of the parts as shown in the drawings, the door catch member 13 is engaged

by portions 18 and 19 of housing 12 with the result that the catch member is maintained against rotation. Being so maintained, the latch arm 59 extends substantially horizontally, see Figures 1, 4 and 5, and when in this position the latch member can readily engage a suitable stop member or other abutment on, for example, the door jamb to maintain the panel type door securely locked. As an example, Figure 5 discloses a stop member 63, said stop member being engaged by the latch arm 59 to maintain the door 10 in closed position.

When it is desired to release the latch arm, i. e. to unlock the panel type door, the operation is as follows: The index rings 38 and 44 are rotated until, for each ring, the correct numeral of the combination is uppermost. To facilitate alignment a vertical alignment marker 64 is formed on the front of panel type door 10. When the index rings 38 and 44 are set correctly, gaps 35 and 33 will be aligned, respectively, with projections 46 and 47. Pressure inward on spindle 24 will force the housing 12 backward against the bias of spring 30, projections 46 and 47 passing through gaps 35 and 33, respectively, until the projecting portions or lugs 18 and 19 on housing 12 pass from within openings 20 and 21 in catch member 13. When this occurs, index ring 38 can be rotated counter clockwise and, due to the frictional engagement between the leather lining 62 and the outer surface of tumbler 22, the latch arm 59 will be rotated downward as shown by the dotted line path outlined in Figure 5. This is movement of the door catch member 13 from door lock to door release position. This movement, of course, removes the latch arm 59 from obstructing opening of the panel type door 10 and the latter can be swung to open position.

When it is desired to re-lock the door, the index rings are again set to correct position whereupon gaps 35 and 33 are aligned to permit projections 46 and 47 to pass therethrough toward the panel door 10. If perchance openings 20 and 21 are not correctly aligned with respect to the ends of portions 18 and 19, these ends will abut against arcuate members 52 and 53 and, simply by turning index ring 38, the openings 20 and 21 can be brought opposite portions 18 and 19 whereupon these portions will slip to a slight extent into the openings under the influence of spring 30 and thereby hold the door catch member 13 so that the gap 33 may be aligned with projection 47 so that the projections 46 and 47 may pass through the gaps 35 and 33 respectively in the direction of the door and the portions 18 and 19 may extend completely into the openings 20 and 21 of the door catch member 13. The index rings 38 and 44 are then turned to disalign the said projections and gaps and thus the lock is again in locking condition. Thus the door catch member 13 can be moved from door release to door lock position wherein latch arm 59 again obstructs opening of door 10. Movement of the housing 12 and projections 46 and 47 is shown in dotted outline in Figure 2, and the movement indicated there is sufficient for the portions 18 and 19 to clear from within openings 20 and 21.

It will thus be seen that I have shown and described a permutation lock assembly for use with a panel type door in which the lock parts can be made of relatively light and inexpensive metal parts. For example, the backing plate 14 can be made of thin gauge sheet metal. Likewise, the housing 12 can be made of thin gauge sheet metal and the tumblers 22 and 23 and the spindle 24 can be formed from ordinary metal stock. Two

index set members are provided to give the advantages of a permutation assembly but even this assembly is of simplified nature to keep the cost of the whole lock assembly to a low figure. The housing member 12, while performing its normal function of housing and protecting the major portion of the lock parts, also forms an operative part of the lock assembly thus giving it a dual function and keeping the number of parts down. While the door catch member 13 is illustrated as being a rotatable member it will be apparent to those skilled in the art that the exact type of mechanical movement of the catch member is not controlling as long as the catch member coacts with the housing 12 in the manner described above.

Accordingly, while I have described and illustrated a preferred embodiment of my invention, I wish it to be understood that I do not intend to be restricted solely thereto, but that I do intend to include all modifications thereof which would be readily apparent to one skilled in the art and which come within the spirit and scope of my invention.

I claim as my invention:

1. A permutation lock comprising a plurality of concentric hollow cylindrical tumblers, a housing surrounding a portion of each of said tumblers, means on said housing positionable in locking relation with means on said tumblers to prevent movement of said housing with respect to said tumblers, means to position said tumbler means to allow movement of said housing with respect to said tumblers, and means to move said housing when said tumbler means are set to allow movement of said housing, said last named means extending through said tumblers.

2. A permutation lock comprising a plurality of concentric hollow cylindrical tumblers, a fence on each tumbler, a housing surrounding a portion of each of said tumblers, said surrounded portion having the fence thereon, projections on said housing corresponding in number to the number of fences, means to position said fences in locking relation with said projections to prevent movement of said housing with respect to said tumblers, means to position said fences to allow movement of said housing with respect to said tumblers, and means to move said housing when said fences are positioned to allow such movement, said last named means extending through said tumblers.

3. A permutation lock comprising a plurality of concentric hollow cylindrical tumblers, a fence on each tumbler, a cup shaped housing having a portion positioned concentrically of said tumblers and surrounding a portion of each of said tumblers, said surrounded portion having the fence thereon, projections on said housing corresponding in number to the number of fences, said projections extending inwardly of said housing, means to position said fences in locking relation with said projections to prevent movement of said housing with respect to said tumblers, means to position said fences to allow movement of said housing with respect to said tumblers, and a spindle member attached to said housing and extending axially of said tumblers, said spindle member being movable axially of said tumblers to move said housing with respect to said tumblers when said fences are positioned to allow such movement.

4. A permutation lock comprising a hollow cylindrical tumbler, a fence on said tumbler, a cup-shaped housing surrounding said fence, said

7. housing being positioned concentrically of said tumbler, a projection extending inwardly from said housing, means to position said fence in locking relation with said projection to prevent movement of said housing with respect to said tumbler, means to position said fence to allow movement of said housing with respect to said tumbler, a spindle member attached to said housing, said spindle member being positioned axially of said tumbler and extending therethrough, and resilient means positioned between said spindle member and said tumbler, said resilient means engaging said spindle member and said tumbler to urge the spindle member outward with respect to the tumbler, and said spindle member being movable inwardly of said tumbler against the bias of said resilient means to move said housing with respect to said tumbler when the fence is positioned to allow such movement.

5. A door lock mechanism comprising a door catch member, means supporting said member for movement from door lock to door release position and vice versa, a permutation mechanism, a housing for said permutation mechanism, said housing being positioned adjacent to said permutation mechanism, locking means on said housing, said permutation mechanism having portions engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism portions in non-locked relation with the locking means on said housing, and means to then move said housing projections out of engagement with the means on said door catch member normally engaged thereby, said catch member then being freed for movement to door release position.

6. A door lock mechanism adapted for use with a panel member having front and rear sides and also having an opening extending therethrough, said mechanism comprising a door catch member, means supporting said door catch member for movement from door lock to door release position and vice versa, a permutation mechanism adapted to extend through the opening in said panel member, a housing for said permutation mechanism said housing being positioned adjacent to said permutation mechanism, locking means on said housing, said permutation mechanism having portions engageable by said locking means to maintain said permutation mechanism and housing in locked relation, projections on said housing, means on said door catch member normally engaged by said projections to maintain said catch member in door locking position when said permutation mechanism and housing are in locked relation, means to set said permutation mechanism portions in non-locked relation with the locking means on said housing, and means adapted to be operated from the front side of the panel member to then move said housing projections out of engagement with the means on said door catch member normally engaged thereby, said catch member then being freed for movement to door release position.

7. A door lock mechanism adapted for use with a panel member having an opening extending therethrough, said mechanism comprising a door catch member adapted to be positioned adjacent

8. to said panel member, said catch member also having an opening extending therethrough and said opening being adapted to be aligned with the opening in the panel member, a permutation mechanism extending through the catch member opening and adapted to extend through the panel member opening, said permutation mechanism supporting said catch member for movement from door lock to door release position and vice versa, a housing for said permutation mechanism, said housing being positioned adjacent to said permutation mechanism, locking means on said housing, said permutation mechanism having portions engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism portions in non-locked relation with the locking means on said housing, and means to then move said housing projections out of engagement with the means on said door catch member normally engaged thereby, said catch member then being freed for movement to door release position.

9. A door lock mechanism adapted for use with a substantially flat panel member having front and rear sides and having an opening extending therethrough, said mechanism comprising a door catch member adapted to be positioned adjacent to the rear side of said panel member, means supporting said catch member for movement from door lock to door release position and vice versa, said catch member being constructed and arranged whereby said movement is in a path parallel to the rear side of said panel member when said catch member is positioned adjacent to said rear side, a permutation mechanism adapted to extend through the opening in said panel member, a housing for said permutation mechanism, said housing being positioned adjacent to said permutation mechanism, locking means on said housing, said permutation mechanism having portions engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism portions in non-locked relation with the locking means on said housing, and means adapted to be operated from the front side of the panel member to then move said housing projections out of engagement with the means on said door catch member normally engaged thereby, said catch member then being freed for movement to door release position.

10. A door lock mechanism adapted for use with a panel member having front and rear sides and also having an opening extending therethrough, said mechanism comprising a door catch member adapted to be positioned adjacent to the rear side of the said panel member, means supporting said catch member for movement from door lock to door release position and vice versa, a permutation mechanism adapted to extend through the opening in said panel member, a housing surrounding a part of said permutation mechanism, said housing also being adapted to be positioned adjacent the rear side of said panel member, locking means on said housing, said permutation

mechanism having portions engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism portions in non-locked relation with the locking means on said housing, and means adapted to be operated from the front side of the panel member to then move said housing projections out of engagement with the means on said door catch member normally engaged thereby, said catch member then being freed for movement to door release position.

10. In combination, a door lock mechanism and a substantially flat panel member having front and rear sides, said panel member having an opening extending therethrough, said lock mechanism comprising a backing plate positioned in spaced parallel relation to said panel member, means attaching said backing plate to the rear side of said panel member, said backing plate also having an opening extending therethrough and said opening being aligned with the opening in said panel member, a door catch member positioned between said backing plate and said panel member, means supporting said catch member for movement from door lock to door release position and vice versa, a permutation mechanism extending through the openings in said backing plate and said panel member, a housing for said permutation mechanism, said housing being positioned adjacent to said permutation mechanism, locking means on said housing, said permutation mechanism having portions engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism portions in non-locked relation with the locking means on said housing, and means to then move said housing projections out of engagement with the means on said door catch member normally engaged thereby, said catch member then being freed for movement to door release position and said housing moving means being operable from the front side of said panel member.

11. A door lock mechanism adapted for use with a panel member having front and rear sides and also having an opening extending therethrough, said mechanism comprising a door catch member adapted to be positioned adjacent to the rear side of said panel member, means supporting said catch member for movement from door lock to door release position and vice versa, a plural tumbler permutation mechanism adapted to extend through the opening in said panel member, a housing surrounding a part of said permutation mechanism, locking means on said housing, said permutation mechanism having tumbler members engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism tumbler members in non-locked relation

with the locking means on said housing, and means adapted to be operated from the front side of the panel member to then move said housing projections out of engagement with the means on said door catch member normally engaged thereby, said catch member then being freed for movement to door release position.

12. A door lock mechanism adapted for use with a substantially flat panel member having front and rear sides and also having an opening extending therethrough, said mechanism comprising a door catch member adapted to be positioned adjacent the rear side of said panel member, means supporting said catch member for movement from door lock to door release position and vice versa, said catch member being constructed and arranged whereby said movement is in a path parallel to the rear side of said panel member when said catch member is positioned adjacent to said rear side, a plural tumbler permutation mechanism adapted to extend through the opening in said panel member, said catch member having an opening therethrough and said permutation mechanism extending through said opening, a housing surrounding a part of said permutation mechanism, locking means on said housing, said permutation mechanism having tumbler members engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism tumbler members in non-locked relation with the locking means on said housing, and means adapted to be operated from the front side of the panel member to then move said housing projections out of engagement with the means on said door catch member normally engaged thereby, said catch member then being freed for movement to door release position.

13. In combination, a door lock mechanism and a substantially flat panel member having front and rear sides, said panel member also having an opening extending therethrough, said lock mechanism comprising a backing plate positioned in spaced parallel relation to said panel member, means connecting said backing plate to the rear side of said panel member, a door catch member positioned between said backing plate and panel member, means supporting said catch member for movement from door lock to door release position and vice versa, said backing plate and said catch member each having an opening therethrough and said openings being aligned with each other and with the opening in the panel member, a plural tumbler permutation mechanism extending through said openings, a housing surrounding a part of said permutation mechanism, locking means on said housing, said permutation mechanism having tumbler members engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism tumbler members in non-locked relation with the locking means on said housing, and means to then move said housing projections out of en-

11

gagement with the means on said door catch member normally engaged thereby, said catch member then being freed for movement to door release position and said housing moving means being operable from the front side of said panel member.

14. A door lock mechanism comprising a door catch member, a plural tumbler permutation mechanism, said catch member engaging one of the tumblers of said permutation mechanism and being supported thereby for movement from door lock to door release position and vice versa, a housing for said permutation mechanism, said housing being positioned adjacent to said permutation mechanism, locking means on said housing, said permutation mechanism having tumbler members engageable by said locking means to maintain said permutation mechanism and housing in locked relation, projections on said housing, means on said door catch member normally engaged by said projections to maintain said catch member in door lock position when said permutation mechanism and housing are in locked relation, means to set said permutation mechanism tumbler members in non-locked relation with the locking means on said housing, and means to then move said housing projections out of engagement with the means on said door catch member normally engaged thereby, said catch member then being movable to door release position upon actuation of the tumbler engaged thereby.

15. A door lock mechanism adapted for use with a panel member having an opening extending therethrough, said mechanism comprising a door catch member adapted to be positioned adjacent to said panel member, said catch member also having an opening extending therethrough and said opening being adapted to be aligned with the opening in said panel member, a permutation mechanism extending through the catch member opening and adapted to extend through the panel member opening, said permutation mechanism including a plurality of hollow cylindrical tumblers, a cup-shaped housing surrounding a portion of each of said tumblers, locking means on said housing, means on said tumbler members engageable by said locking means to maintain said permutation mechanism and housing in locked relation, a spindle member attached to said cup-shaped housing, projections

12

on said housing, means on said door catch member normally engaged by said projections to maintain said catch member in door lock position when said permutation mechanism and housing are in locked relation, means to set said tumbler member means in non-locked relation with the locking means on said housing, said spindle member then being movable axially of said tumblers to move said housing projections out of engagement with the means on said door catch member normally engaged thereby, said catch member then being freed for movement to door release position.

16. In a door lock mechanism having a cylindrical lock member supported by and extending through a panel member, a door catch member surrounding said lock member and being movable from door lock position to door release position and vice versa, said catch member comprising oppositely disposed arcuate members, a friction liner on each of said arcuate members, said liners engaging the outer surface of said cylindrical lock member, and means urging said friction liners against the outer surface of said cylindrical lock member whereby rotation of said lock member causes rotation of said catch member.

17. In a door lock mechanism having a cylindrical lock member supported by and extending through a panel member, a door catch member surrounding and engaging said cylindrical lock member and being movable therewith from door lock to door release position and vice versa, said catch member comprising oppositely disposed arcuate members positioned concentric with said cylindrical lock member, a latch arm forming an extension of one of said arcuate members, and means connecting said arcuate members together.

CLAUDE J. AMO.
